PLUNGER SHAVING BRUSH

Filed Aug. 23, 1927

Inventor
Maurice Alland,
By
J. Stuart Freeman,
Attorney.

UNITED STATES PATENT OFFICE.

MAURICE ALLAND, OF ATLANTIC CITY, NEW JERSEY.

PLUNGER SHAVING BRUSH.

Application filed August 23, 1927. Serial No. 214,842.

The object of the invention is to provide improvements in shaving brushes, and particularly in that type which contains liquid soap or the like for repeated shaving without the necessity of carrying soap separately from the brush, either in cake, cream, or liquid form.

Another object is to provide a shaving brush which comprises several highly advantageous details, including a telescoping jacket or sleeve which is adapted to surround and protect the brush when the latter is not in use; an efficient plunger mechanism operative to effect the filling of the reservoir and when desired to eject a suitable quantity of liquid soap into the bristles of the brush; a simple yet positively acting valve structure whereby soap is normally prevented by a portion of the plunger from flowing from the reservoir into said bristles; and other details of construction and operation such as are hereinafter brought out in the following description, when read in conjunction with the accompanying drawings, in which Fig. 1 is a side elevation of one embodiment of the invention with a small portion thereof in section and with the bristles of the brush covered; Fig. 2 is a similar view showing the bristles exposed and the plunger handle partially withdrawn; Fig. 3 is a longitudinal section of the device; and Fig. 4 is an upper end or top plan view of the same.

Referring to the drawings, a cylinder 1 is externally provided at one end with screw threads 2, and at its opposite end with similar threads 3, adjacent to a reduced end portion 4, which in turn is externally threaded at 5. Surrounding said cylinder and longitudinally slidable thereon is a sleeve 6, one inner end portion of which is provided with threads 7, adapted to engage either the set of threads 2 or 3 for purposes hereinafter described.

A brush is employed which comprises bristles 8, secured within a circular block 9, having an axial bore 10, and terminating opposite to said bristles in a hollow cylindrical flange 11, which is internally threaded so as to normally engage the threads 5 of the reduced end portion of the cylinder 1. Within the said flange there is secured an apertured disc 12, in any suitable manner as for instance in engagement with the threaded surface of the said flange, while a second disc 13, threaded upon its periphery, is nor-

mally secured within and in threaded engagement with internal threads 14, in the otherwise open end portion of the cylinder 1. This last-named disc is provided with a central aperture 15, communicating with the bore of an integral tube 16, which normally extends into the bore 10 of the brush block 9.

The end of the cylinder 1 opposite to said brush is also provided internally with threads 17, which normally receive the reduced threaded portion 18 of a plug, having an enlarged flange or knob 19 provided with a notched or knurled outer surface to assist in its manual engagement, said plug being provided with an axial bore 20 into which is secured, in any suitable manner, the end portion of a rod 21, which extends slidably thru the bore 22 of a disc closure 23 for the adjacent end of said cylinder 1.

Proceeding towards its inner end, the rod 21 is first provided with an externally threaded portion 23' adapted to engage the threaded bore 24 of a disc 25, against which latter abuts a centrally apertured leather or similar washer 26. Next, said rod is provided with a plane flange 27, which abuts against the inner surface of said washer, when the threaded portion 23' of said rod is in engagement with the disc 25. Beyond said last-named flange, said rod is provided with a shoulder 28, against which is positioned a washer 29, surrounding a reduced terminal portion 30, which normally is positioned within the aperture 15 of the closure disc 13 and extends into the bore of the discharge tube 16.

In the operation of the device when not in use, the several parts are in the respective positions shown in Fig. 1, with the sleeve 6 surrounding and protecting the bristles 8, and the terminal portion 30 of the plunger rod 21 entering the discharge tube 16, so as to prevent the accidental emission of liquid soap or the like into the bristles from within the reservoir defined by the first-named cylinder 1, and the end discs 13 and 23.

If the reservoir is empty, the sleeve 6 is released from engagement with the threads 3, and is moved longitudinally into the withdrawn position shown in Figs. 2 and 3, and into engagement with the threads 2. The brush 8-9 is then withdrawn from engagement with the reduced end 4 of the reservoir cylinder, thereby exposing the tube 16. The knob 19 is then rotated to loosen its threaded portion 18 from engagement with the

threads 17 of the reservoir cylinder, and then if the threaded portion 23' of the rod 21 is not in engagement with the aperture 24 of the disc 25, continued rotation of said 5 knob and the drawing outwardly of the said rod will effect such an engagement.

10 Immersing the tube 16 in liquid soap or the like and withdrawing said rod and plunger 25-26-27 (after having previously forced all possible air from within the reservoir) operates to draw liquid into the reservoir cylinder 1 until the plunger reaches its innermost or highest position as shown in Fig. 1. If the brush is not to be used at 15 once, the knob 19 is rotated in the reverse direction until the rod is disengaged from the plunger, after which the former is forced into its innermost position until the reduced terminal portion 30 enters and closes 20 the discharge tube 16. The brush is then replaced in its normally operative position as shown in the drawings.

25 When the device, having been filled, is to be used for moistening, soaping and lathering the beard, the knob and attached rod are withdrawn, and rotated into engagement with the said plunger, after which the knob-rod-plunger unit is forced into the reservoir until the desired quantity of 30 liquid is ejected into the bristles. The knob and rod are then rotated so as to disengage them from the plunger, leaving the latter in whatever position it may be, and the former being returned to their innermost positions, closing the discharge tube and permitting the soaped brush to be used in the 35 usual manner.

40 This operation can obviously be repeated several times with but a single filling of the reservoir, after which the latter must be re-filled as hereinbefore described. In each case, after the user has finished with the brush, the sleeve is returned to its original 45 position in which it protects the bristles as previously referred to. Also, it should be noted that the construction of the improved brush makes it possible to cleanse the same, whenever desired, with the least possible difficulty, and altho the parts are designed to 50 be used for many years without appreciable wear or breakage, they can be removed and replaced with the least possible difficulty.

Having thus described my invention, what I claim and desire to protect by Letters Patent 55 of the United States is:—

1. A shaving brush, comprising a reservoir cylinder, an apertured brush block detachably carried by one end of said cylinder, an apertured closure for said cylinder independent of said block and provided with an integral discharge tube extending into the aperture of said block, a plunger within 60 said cylinder, and a rod adapted to be con-

nected to and disconnected from said plunger at will, and provided with a reduced cylindrical end portion of substantially the same diameter and adapted to extend well into the bore of said tube to break and force dried soap therethrough. 65

2. A shaving brush, comprising a hollow cylinder internally threaded at its opposite ends and externally threaded at one end, a plunger within said cylinder, a closure for one end of said cylinder, a rod extending slidably through said closure and adapted to be detachably connected to said plunger and provided with a reduced cylindrical end portion, an apertured brush-supporting block detachably connected to the external threads of said cylinder and forming a closure for the opposite end thereof, and an auxiliary closure for said opposite end removably secured to the internal threads thereof and provided with an aperture and an aligned nozzle normally extending through the aperture in said block, the reduced end of said rod when in contracted position extending slidably into said nozzle to break and force dried soap therethrough, said rod being provided with a threaded head which 80 when in contracted position engages the threads of said first end of said cylinder. 85

3. A shaving brush, comprising a hollow cylinder both internally and externally threaded at its opposite end, a plunger within said cylinder, a closure adjustably engaging the internal threads of one end of said cylinder, a rod extending slidably through said closure and adapted to be detachably connected to said plunger and provided with a reduced cylindrical end portion, an apertured brush-supporting block detachably connected to the external threads of and forming a removable closure for the opposite end of said cylinder, an auxiliary closure for said opposite end removably and adjustably secured to the internal threads thereof and provided with an aperture and an aligned tubular nozzle normally extending through the aperture in said block, the reduced end of said rod when in contracted position extending slidably into said nozzle to break and force dried soap therethrough, said rod being provided with a threaded head which when in contracted position engages the internal threads of said first end of said cylinder, and a sleeve slidably engaging the outer surface of said block as a bearing and having its opposite end provided with internal threads which are adapted to cooperate at will with the external threads upon the opposite ends of said cylinder. 100 105 110 115 120

In testimony whereof I have affixed my signature.

MAURICE ALLAND.
